UNITED STATES PATENT OFFICE.

WALTER F. KOKEN, OF ST. LOUIS, MISSOURI.

DESIGN FOR A CHILD'S HAIR-CUTTING CHAIR.

48,322.

Specification for Design.

Patented Dec. 21, 1915.

Application filed October 11, 1915. Serial No. 55,334. Term of patent 14 years.

To all whom it may concern:

Be it known that I, WALTER F. KOKEN, a citizen of the United States, residing at St. Louis, Missouri, have invented a certain new, original, and ornamental Design for a Child's Hair-Cutting Chair, of which the following is a specification, reference being had to the accompanying drawing, forming part thereof.

The figure of the drawing is a perspective view of my new design for a child's hair cutting chair.

I claim:

The ornamental design for a child's hair cutting chair, as shown.

WALTER F. KOKEN.

Witnesses:

GEORGE G. ANDERSON,
WILBUR L. MCKIM.
